UNITED STATES PATENT OFFICE.

JOSEPH MACCHIARELLA, OF PATERSON, NEW JERSEY.

SHUTTLE GUARD FOR LOOMS.

Application filed December 1, 1926. Serial No. 151,905.

This invention relates to shuttle guards for looms and has for its object to provide a construction which is simple to manufacture and more efficient in use than those 5 heretofore proposed.

With these and other objects in view the invention consists in the novel details of construction and arrangements of parts, all 10 as will be more fully disclosed hereinafter and particularly pointed out in the claims.

Referring to the accompanying drawings forming a part of this specification in which like numerals designate like parts in all the views:

15 Fig. 1 is an elevated view with parts removed showing this invention in operation on a shuttle;

Fig. 2 is a transverse sectional view with parts omitted, taken as on the line 2—2 of 20 Fig. 1, and looking in the direction of the arrows;

Fig. 3 is a view similar to Fig. 2 with the shuttle guard in raised position; and

25 Fig. 4 is a sectional view taken as on the line 4—4 of Fig. 2 and looking in the direction of the arrows.

1 represents a suitable support or framework carrying the lay 2 in which the shuttle 3 is adapted to travel from a shuttle box 4 30 at one side of the loom to a corresponding shuttle box, not shown, on the other side of the loom, the shuttle being moved from one side to the other of the loom in the usual and well known manner. In order that the 35 shuttle 3 may not become damaged of itself, or do damage to the shuttle box into which it is projected, there is provided at each end of the lay, a device made in accordance with this invention which will so straighten out 40 the course of the shuttle that said damage may not be done.

This guard comprises a roller 10 having rigidly secured in its center a bushing 11 adapted to revolvably engage a sleeve 12 inserted therethrough and surrounding a bolt 13 carried by one leaf 14 of a hinge whose other leaf 15 is adapted to be rigidly secured as by a bolt 16 to the cover plate 17 of the lay 2. The sleeve 12 makes possible 45 the mounting of the bolt 13 in substantially a perpendicular relation with the leaf 14 of the hinge, said sleeve 12 being confined between said leaf 14 and a washer 18 clamped by the nut 19, all as will be readily understood with particular reference to Fig. 4.

50 The roller 10 and its supporting hinge are

both so disposed on the loom that the roller 10 when in operative position will have its axis formed by the bolt 13 disposed in a horizontal plane, or in other words, the roller 10 when in operation will contact with the upper surface of the shuttle 3, the roller 10 being adapted for ready rotation about its axis. The roller 10 is preferably made of rubber and said roller is so disposed that it 55 extends below the plane of the top of the shuttle in the lay about $\frac{1}{16}$ of an inch or slightly less, so that when the shuttle is about to enter the box 4, it will strike the rubber roller 10, thus straightening out the 60 course of the shuttle.

In order that the shuttle 3 may be removed or taken out of the shuttle box 4 if necessary, the roller 10 and its hinge support is adapted to be raised into an elevated position so 75 that said shuttle may be readily removed. With particular reference to Figs. 2 and 3 it will be seen that the former shows the roller 10 in down or operative position, whereas in Fig. 3 the roller 10 is shown turned about 80 the pivot or hinge so that said roller and its axle 13 are raised to a position well above the top surface, represented by the dash line 20 of the shuttle 3. In order that the said roller may be retained in its elevated or in- 85 operative position, the leaf 14 of the supporting hinge has riveted or otherwise secured thereto a spring 25 whose free end is turned at substantially a right angle to its base portion 26 and clamped as clearly 90 shown in Fig. 4 to spring over the edge 27 of the other leaf 15 of the supporting hinge. Thus it will be readily seen that the roller 10 may effectively be retained in its raised 95 position due to the friction of the spring 25 hook-like end of the member 25, but readily lowered by applying pressure to the roller 10 to disengage said spring like hook 25 from its coacting edge 27 of the leaf 15 of the supporting hinge for the roller.

100 Thus it will be seen that by this invention there is provided a device combining a yieldable roller which is adapted to frictionally engage a moving shuttle when in one position, with hinged means supporting said 105 roller to permit movement of the same out of engagement with said shuttle, said roller being attached to one leaf only of the hinge, Further this device has combined therewith spring means comprising the clamp or clip 110 25 secured to the leaf of the hinge supporting the roller, said clip coacting with the

edge of the other leaf of the hinge to secure the roller in a position out of engagement with the shuttle.

It is obvious that those skilled in the art may vary the details of construction as well as the arrangements of parts without departing from the spirit of the invention, therefore it is not desired to be limited to the forgoing disclosure except as may be demanded by the claims.

What is claimed is:

1. In a device of the character described the combination of a yieldable roller adapted to frictionally engage a moving shuttle when in one position; hinged means to permit movement of said roller out of engagement with said shuttle; and spring clamping means to secure said roller in said last named position.
2. In a device of the character described the combination of a roller adapted to frictionally engage a moving shuttle when in one position; means to permit movement of said roller out of engagement with said shuttle; and means comprising a spring clip secured to said last named means to secure said roller in said last named position.
3. In a device of the character described

the combination of a roller adapted to frictionally engage a moving shuttle when in one position; means comprising a hinge one leaf of which supports said roller to permit movement of said roller out of engagement with said shuttle; and means to secure said roller in said last named position.

4. In a device of the character described the combination of a roller adapted to frictionally engage a moving shuttle when in one position; means comprising a hinge one leaf of which supports said roller to permit movement of said roller out of engagement with said shuttle; and means coacting with the other leaf of said hinge to secure said roller in said last named position.

5. In a device of the character described the combination of a roller adapted to frictionally engage a moving shuttle when in one position; means comprising a hinge one leaf of which supports said roller to permit movement of said roller out of engagement with said shuttle; and means carried by the roller supporting leaf coacting with the other leaf of said hinge to secure said roller in said last named position.

In testimony whereof I affix my signature.

JOSEPH MACCHIARELLA.
